US00D391237S

United States Patent

[19]

Iino

[11] Patent Number: Des. 391,237

[45] Date of Patent: **Feb. 24, 1998

[54] ELECTRONIC COMPUTER

[75] Inventor: **Masaaki Iino**, Saitama-ken, Japan[73] Assignee: **Kabushiki Kaisha Toshiba**, Kawasaki, Japan

[**] Term: 14 Years

[21] Appl. No.: 68,487

[22] Filed: Mar. 21, 1997

[30] Foreign Application Priority Data

Nov. 13, 1996 [JP] Japan 8-34081

[51] LOC (6) Cl. 14-02

[52] U.S. Cl. D14/106

[58] Field of Search ..... D14/100, 106, D14/113, 115, 126-129; D18/1, 7; 235/145 A, 145 R; 341/22, 23; 345/104, 156, 168, 173, 87, 160; 361/680-686; 364/708.1; 400/486, 489
